UNITED STATES PATENT OFFICE.

GEORGE NIEDERMAYER, OF CLEVELAND, OHIO, ASSIGNOR TO THE TELL MACHINE & TOOL CO., OF CLEVELAND, OHIO, A CORPORATION OF OHIO.

EXPANSIBLE REAMER.

Application filed October 25, 1919. Serial No. 333,321.

To all whom it may concern:

Be it known that I, GEORGE NIEDERMAYER, a citizen of Hungary, resident of Cleveland, county of Cuyahoga, and State of Ohio, have invented new and useful Improvements in Expansible Reamers, of which the following is a specification, the principle of the invention being herein explained and the best mode in which I have contemplated applying that principle, so as to distinguish it from other inventions.

My invention relates to expansible reamers, its object being to construct a reamer of this character which may be economically manufactured, and which will be efficient in the performance of its functions.

The said invention consists of means hereinafter fully described and particularly set forth in the claims.

20 The annexed drawings and the following description set forth in detail certain means embodying my invention, the disclosed means, however, constituting but one of the various mechanical forms in which the principle of the invention may be applied.

In said annexed drawings:

Figure 1 represents a side elevation of a reamer embodying my invention.

30 Figure 2 represents an axial section of said reamer, taken upon the plane indicated by line II—II in Figure 4.

Figure 3 represents an axial section taken upon the plane indicated by line III—III in Figure 4.

35 Figure 4 represents a cross section taken upon the plane indicated by line IV—IV in Figure 2.

Figure 5 represents a cross section taken upon the plane indicated by line V—V in Figure 2.

Figure 6 represents a cross section taken upon the plane indicated by line VI—VI in Figure 2.

40 Figure 7 represents a cross section taken upon the plane indicated by line VII—VII in Figure 2.

Figure 8 represents a side elevation of an expansible cylinder reamer embodying my invention.

50 Figure 9 represents a plan of said cylinder reamer.

Figure 10 represents a cross section of the cylinder reamer.

Figure 11 represents a side elevation of the interior blade-actuating member or 55 spool.

Figure 12 represents a top plan of said spool, and Figure 13 a bottom plan thereof.

Figure 14 represents a side elevation of 60 one of the blades, and Figure 15 a top plan thereof.

The illustrated embodiment of my invention, referring first to Figures 1 to 7 inclusive, and Figures 11 to 14 inclusive, 65 comprises a cylindrical hollow body member 1 having an interior cylindrical bore 2, the upper end of which is threaded, as at 3. The lower end of this bore is contracted, as at 4, which contracted portion is provided with a bushing 5 forming a cylindrical bearing surface 6. The intermediate portion of the body member is provided with radially extending slots 7, Figures 4 to 7 inclusive, and in these slots are 70 seated reamer blades 8. The interior edges of each of these blades is made circular in cross section, whereby a longitudinal cylindrical bearing surface 9 is formed. This bearing surface is inclined relatively to the 75 cutting edges 10 of the blade, as shown in Figures 2 and 14, and has a circumference greater than a semi-circle.

Extending into the interior of the body member is a rotatable member 11 provided 85 with threads 12 which engage the threads 3. The inner end of this member 11 is provided with a pilot 14 which extends into and engages the bearing surface 6 of the bushing 5. Adjacent to this pilot is formed 90 a thread 15, which is engaged by a nut 16. Above this nut is formed a cylindrical bearing surface 17, upon which is mounted an actuating member or spool 18, its upper end engaging a shoulder 19 formed upon the 95 member 11. This spool 18, Figure 11, is preferably reduced at its middle portion, as shown, so as to form two collars 18' 18''. These collars are formed with inclined slots 20 and 21 respectively, forming slideways, 100 whose cross sections correspond with the cross section of the inner end portions of the blades 8. The latter are seated in these slots, and are slidable therein longitudinally, the form of the bearing surfaces of 105 the blades and slots being such that these

bearing surfaces will be secured in the slots so that when the spool is moved longitudinally in the body of the reamer by turning the rod 11, that is, in the direction of the reamer's axis, the blades will slide in the slots 7 and be moved inwardly or outwardly according as the spool is moved in one or the other longitudinal direction, all as will be understood. It will be observed that the pilot 14 holds the lower end of the member 11 in perfect alignment, and thus facilitates the actuating function of the spool, and that when the spool is moved longitudinally, it is held against rotation relatively to the body member, while being rotatable with reference to the rod 11.

A lock nut 22 is provided to fix the member 11 in place after the required position of the blades has been imparted.

In order to provide for compensation due to wear of the bearing surfaces 9 in the slots 7, I provide in the spool 18 a plurality of interiorly threaded cylindrical recesses 23 in which are seated adjusting screws 24. These recesses intersect the inner ends of the slots 23, as shown in Figures 6 and 13, so that the screws are adapted to bear against the surfaces 9 and take up any lost motion which may exist between these adjacent parts.

In the modified form shown in Figures 8, 9 and 10, which is particularly adapted for use as a cylinder reamer, the construction is substantially the same as that above described, the main difference consisting in the provision of a hexagon head 25 formed on the body member, as shown in Figure 8, and the provision of dovetailed grooves or slots 20 and 21, as shown in Figure 10, instead of cylindrical ones.

What I claim is:

1. In an expandible reamer, the combination of a hollow body member formed with radial slots and having an open interiorly threaded end; blades mounted and adapted to slide in said slots; an actuating member in said body member formed with longitudinally inclined slideways, the inner ends of said blades being formed with inclined bearings adapted to seat and slide in said slideways; and a rod having threaded engagement with the interiorly threaded end of said body member, said actuating member being rotatably mounted upon said rod but longitudinally fixed relatively thereto, said actuating member being removable with said rod through said open threaded end of said body.

2. In an expandible reamer, the combination of a hollow body member, formed with radial slots the bore of said member being contracted at one end to form an axial bearing; blades mounted and adapted to slide in said slots; an actuating member in said body member formed with longitudinal inclined slideways, the inner ends of said blades being formed with inclined bearings adapted to seat and slide in said slide ways; and a rod having threaded engagement at one end with the large bore end of said body member and a pilot at the other end engaging the aforesaid axial bearing, said rod being formed intermediate its ends with a pair of abutments between which said actuating member is rotatably mounted upon said rod.

Signed by me this 16th day of October, 1919.

GEORGE NIEDERMAYER.
